CLAIM

The ornamental design for a guide for a fishing rod, as shown and described.

DESCRIPTION

FIG. 1 is a perspective view of a guide for a fishing rod showing my new design;

FIG. 2 is a front elevational view of the design of FIG. 1, the opposite side being a mirror image thereof;

FIG. 3 is a side elevational view thereof, the opposite side being mirror image of the same;

FIG. 4 is a top plan view thereof;

FIG. 5 is a bottom plan view thereof; and

FIG. 6 is a sectional view thereof taken on line 6—6 of FIG. 4.
